CLAIM

The ornamental design for a spartan golf divot tool as shown and described.

DESCRIPTION

FIG. 1 is a perspective view showing the new, original, and ornamental design of a spartan golf divot tool;

FIG. 2. is a front elevation view thereof;

FIG. 3 is a rear elevation view thereof;

FIG. 4 is a right elevation view thereof, the left side being a mirror image;

FIG. 5 is a top plan view thereof; and,

FIG. 6 is a bottom plan view thereof.

The dash-dash broken lines in FIG. 3 show portions of the spartan golf divot tool that form no part of the claimed design. The uneven broken lines shown represent contour lines and form no part of the claimed design.

The broken lines in the drawings are contour lines which form no part of the claimed design.

1 Claim, 3 Drawing Sheets
